DESIGN FOR A LICENSE PLATE FOR AUTOMOBILES

Francis D. Tweeddale, Pomona, Calif.

Application July 22, 1939, Serial No. 86,180

Term of patent 7 years

To all whom it may concern:

Be it known that I, Francis D. Tweeddale, a citizen of the United States, residing 222 Walnut Street, in the city of Pomona, county of Los Angeles, State of California, have invented a new, original, and ornamental Design for License Plates for Automobiles, of which the following is a specification, reference being had to the accompanying drawing, forming part thereof.

The Fig. 1 is a plan view of a license plate showing my new design.

Fig. 2 is an edge view thereof.

The license plate of my design is substantially thin and flat.

I claim:

The ornamental design for a license plate for automobiles, as shown and described.

FRANCIS D. TWEEDDALE.
